MARIO CARBONE, OF NEW YORK, N. Y.

INTERNAL-COMBUSTION ENGINE.

1,180,376.

Specification of Letters Patent Patented Apr. 25, 1916.

Application filed February 7, 1912. Serial No. 676,039.

To all whom it may concern:

Be it known that I, MARIO CARBONE, residing at New York, in the county of New York and State of New York, have invented 5 certain new and useful Improvements in Internal-Combustion Engines, of which the following is a specification.

This invention relates to internal combustion engines, and more particularly to 10 internal combustion engines of the four cycle type which are adapted to the use of relatively heavy oil fuels.

One of the objects of the invention is to provide an engine of the above character 15 wherein the number of valves employed are reduced, thus reducing the percentage of leakage and simplifying the construction.

Another object is to provide improved 20 valve mechanism for governing a single port which is adapted for both intake and exhaust purposes.

Another object is to provide new and improved starting means for an engine of the above character, whereby initial external 25 heating is eliminated, thus avoiding an uneven expansion of the cylinder head and the associated parts, and the liability of cracking due to such differential expansion.

Another object is to provide means where- 30 by an engine of this character may be started by the use of a minimum amount of compressed air which is used herein as a starting medium.

Still another object is to provide an im- 35 proved means for operating the intake and exhaust controlling valves of a multi-cylinder engine.

A further object is to provide improved 40 means for igniting the explosive mixture in engines of the type described herein.

Other objects will be in part obvious and in part pointed out during the course of the following description of my invention which consists in the features of construction, combinations of elements and arrangements of parts hereinafter described, and the scope of the protection sought will be indicated in the appended claims.

In the accompanying drawings which 50 illustrate a preferred form of embodiment of my invention, Figure 1 is a vertical sectional view taken through an internal combustion engine, constructed in accordance with my invention; Fig. 2 illustrates in ele-

vation and plan a cam device employed for 55 operating the valve mechanism; Fig. 3 is a view similar to Fig. 1, but taken in a plane at right angles thereto and showing a portion of the cylinder and piston; Fig. 4 is a view in sectional elevation, partly 60 schematic, which illustrates certain features of my invention; and Fig. 5 is a view in diagram which illustrates an arrangement of the valve mechanism as adapted for a multi-cylinder engine. 65

Similar reference characters refer to similar parts in the several figures of the drawings.

Referring now to the drawings, and particularly to Figs. 1 to 3 inclusive, the numeral 1 denotes a base member or support for the engine, and 2 a casting which forms a water jacket for the cylinder 3. A portion of the piston is shown at 4, said piston operating in the cylinder 3. Located forwardly of the cylinder 3, and suitably attached to said cylinder and the casing 2 is a casting 5 upon which is supported the valve and other associated mechanism, said casting being preferably made hollow as 80 shown so as to provide a water jacket for the parts which are liable to become superheated during the operation of the engine. This casting 5 is provided with a conically formed recess 6, which leads into the explosion chamber 7. Located at right angles to the valve chamber 7, and extending transversely into the casting 5 is a recess 8 provided with a shoulder 9 upon which rests a member 10 which carries the valve mechanism. The member 10 may be formed in two parts for convenience of assemblage and is provided with a flange 11 which rests upon a shoulder 12 formed exteriorly of the casting 5. 90

Extending upwardly into the casting 5 and suitably secured therein is a fitting 13, said fitting comprising the flange 14 which engages the casting 5, so as to form the water cooling space 15, and said fitting having 100 an upwardly extending intake and exhaust pipe 16. Mounted upon the upper end of the pipe 16 and adapted to be detachably secured thereto is a tubular cap piece 17, said cap piece being provided with a plurality of 105 circularly disposed laminations 18. The upper end of this cap piece is formed into a valve-seat 19, with which co-operates a

puppet valve 20, which is also provided with exterior ribs or laminations 21. The stem 22 of the valve 20 extends upward through the member 10 to a position exteriorly thereof and within said member is provided with a circular bracket 23 which is suitably secured thereto, and resting upon a shoulder 24 formed upon said stem. The lower end of the bracket 23 is provided with a flange 25 upon which rests a coil extensile spring 26, the opposite end of said spring engaging a shoulder 27 formed within the member 10.

Formed in the lower portion of the fitting 14 is a horizontally disposed tubular valve chamber 28, into which leads the intake and exhaust pipe 16, and leading from this valve chamber is an exhaust pipe 29 and leading thereto is an air inlet pipe 30.

20 The numeral 31 in the present instance indicates a sliding piston valve, which fits nicely into the interior of the valve chamber 28 and has a gas-tight sliding engagement with the inner wall thereof. The valve 25 31 is adapted to shut off both the exhaust pipe 29 and the inlet pipe 30, there being a forwardly extending portion 32 which rests over the port 33 into which leads the inlet pipe 30, when the parts are in the position 30 shown in Fig. 1. This forwardly extending part 32 forms a part of a partition 34, which when the valve 31 is moved forwardly in the valve chamber 28 by means which will hereinafter be described, operates to close 35 communication between the intake and exhaust pipe 16 and the exhaust pipe 29. When the valve 31 is in its forward position to close the exhaust pipe 29, the intake pipe 30 will be opened whereby communication 40 will be established between said pipe 30 and the intake and exhaust pipe 16. The valve 31 has attached thereto a stem 35 which extends through the end wall 36 of the valve chamber 28, and pivoted to the outer end of 45 this stem at 37 is a link 38, said link being, in turn, pivoted at 39 to a crank arm 40 provided upon a cam member 41 which is carried upon a shaft 42, and fastened thereto as by means of the key 43. Shaft 42 is adapted 50 to be driven from the crank shaft of the engine by any suitable means. Cam member 41 which is shown in Fig. 2 has resting thereon an anti-friction roller 44 which is journaled upon one end of lever 45, said lever being journaled upon a suitable pivotal support 46, and to the opposite end of this lever at 47 is pivoted a link 48. The opposite end of link 48 is pivoted at 49 to one end of a lever 50 journaled at 51 upon an arm 52 carried upon the valve supporting member 10, and the opposite end of lever 50 is received between collars 53 and 53' fixed upon the stem 22 of the valve 20.

60 It will be noted that the spring 26, operating through the chain of mechanism

just described, maintains the valve 20 against its seat 19 and also holds the anti-friction roller 44 in engagement with the cam 41. And it will be further noted that a rotation of the shaft 42 will, through the 70 crank arm 40 and the cam 41, operate the valves 31 and 20 respectively, the operation of these valves being so timed and proportioned that they will perform their intended functions.

75 Extending transversely through the casting 5 is an aperture 54, said aperture being located adjacent and opposite the laminations 17 of the tubular cap piece 18 and also opposite and adjacent the laminated portions 21 of the valve 20, for a purpose which will be apparent hereinafter.

80 Referring now to Fig. 4 of the drawings, there is positioned in the aperture 54 a hollow fitting 55, the inner end of which is 85 provided with a valve seat 56 with which cooperates a puppet valve 57, said valve being carried upon a stem 58 which extends longitudinally through the fitting 55. The valve 57 is normally held in the position shown by a coil spring 59 which engages a collar 60 fastened upon the stem 58, said spring in turn impinging against a shoulder 61 formed interiorly of a conically formed nozzle member 62 which is carried interiorly of the fitting 55 and has a mouth or port arranged in alignment with the valved exhaust port of the fitting 55. Leading into the interior of the nozzle member 62 is a pipe 64 which leads from a suitable source 100 of compressed air which, in the present instance, is represented by the compressed air tanks 65, there being a valve 66 interposed between the pipe 64 and said tanks.

105 Extending through the wall of the casing 5, and into the valve chamber 7 is an aperture 67, said aperture in Fig. 4 being illustrated as directly opposite the aperture 54, although they are shown at right angles to each other in Figs. 1 and 3, such change being made in Fig. 4 in the interest of clearness of illustration. This aperture is designed to receive a fitting 68, which is secured therein and is provided with an inwardly flaring port having a valve seat 69 adapted to receive a pin valve 70, the stem 71 of which extends outwardly to a position exterior to the fitting 68, said pin valve being normally held closed as by means of an extensile spring 72. Leading into the fitting 68 is a branch pipe 73 which leads from the compressed air pipe 64. Valve 70 is adapted to be operated by means of a bell crank lever 74 pivoted as at 76. Attached to the opposite arm of said bell crank lever is a rod 77, the upper end of which is provided with an anti-friction roller 78 with which is adapted to cooperate a cam member 79 carried upon a transversely extending shaft 80, said shaft being adapted to be 110 115 120 125 130

suitably driven from the engine by means not shown herein. The valve 57 is also operated from this shaft 80 by means of a bell crank lever 81 and a rod 82, the upper end 5 of which is provided with an anti-friction roller 83 which engages a cam 84, said cam being preferably slidably mounted upon the shaft 80 for a reason which will be apparent hereinafter.

10 The reference numeral 85 indicates a spark plug which extends transversely through the wall of the casting 5 and into the explosion chamber 7, said spark plug being adapted to be operated from the cam 15 shaft 80 as by means of the rod 86 and lever 87, a cam 88 slidably mounted upon the shaft coöperating with an anti-friction roller 89 upon the rod 86 to accomplish such operation. It will thus be seen that a 20 rotation of the shaft 80 will operate both the valves 57 and 70, and will also operate the sparking device 85.

90 and 91 respectively indicate fuel tanks, the tank 90 in the present instance being designed to contain a relatively volatile fuel such as gasoline which is designed to be used in the starting operation, as will hereinafter be described, and the tank 91 being designed to contain a relatively heavy oil 25 with which the engine is to be regularly operated. Leading from these tanks are pipes 92 and 93 respectively which merge into a common pipe 94, each of pipes 92 and 93 being independently valved as at 95 and 30 96 respectively. It is intended that one of the valves 95 and 96 shall be closed while the other is open, and I have shown herein diagrammatically valve operating arms 97 and 98 respectively which are connected by 35 a link 99, which link is adapted to be operated by means of a lever 100. By means of this construction it will be seen that when one valve is open the other will be closed. Pipe 94 is provided with a valve 101 which 40 is adapted to be automatically controlled as by means of a governor 102 driven from a beveled gear wheel 103 of the shaft 80, and is also provided with a check valve 104.

105 illustrates the cylinder of a fuel pump, the piston 106 of which is connected by means of a link 107 with an eccentric device 108 upon the shaft 80, so that during the rotation of the shaft the piston 106 will be reciprocated to pump the fuel from either 50 of the tanks 90 or 91. Leading from the pump 105 is a pipe 109 provided with a check valve 110 and leading from this pipe is a pipe 111 which enters the fitting 68. Pipe 109 also leads through a valve 112 to 55 pipe 113, which enters the fitting 55.

Having thus described this embodiment of my invention, the operation thereof will now be described, and this description will first have reference to the method of starting the engine.

In starting engines of this character, it is customary to "bar back" the engine, that is to say, the fly wheel of the engine is moved mechanically until the piston is carried to the inner end of the cylinder. When this 70 operation has been performed in the present structure, with the valves 95 and 112 open, the fuel pump will have been operated sufficiently to force a quantity of the volatile fuel from the tank 90 through the pipes 92, 75 94, 109, 113, and 111 into the fittings 55 and 68. The cam shaft 80 will also have revolved sufficiently to cause the cam 84 and its associated mechanism to open the valve 57. The compressed air is now turned on at 80 the valve 66 and flows through the pipe 64 into the nozzle member 62, and thence into the explosion chamber 7. This compressed air, passing through the nozzle member 62, has an inspiring action on the volatile fuel 85 in the fitting 55, whereby said fuel is carried into the explosion chamber in the form of a spray and mixed with the compressed air to form an explosive mixture. The compressed air moves the piston 4 rearwardly 90 and when the greater part of the initial stroke of the piston has been completed, the spark plug 85 will be operated by the cam 88, to explode the mixture whereby additional impetus will be given the piston. 95 Just prior to the completion of the initial stroke of the piston, and prior to ignition of the explosive mixture, the cam 79 engages the roller 78 whereby the valve 70 will be opened and a quantity of the volatile fuel 100 in atomized form will be projected into the explosion chamber. This will further enrich the mixture which is to be exploded. The return stroke of the piston will force the products of combustion out through the 105 intake and exhaust pipe 16, the valve chamber 28 and the exhaust pipe 29. The engine will thereafter operate in the same manner as an ordinary four-cycle engine, the volatile fuel in the tank 90 being utilized as the 110 fuel to form the explosive mixture with the air entering the explosion chamber through the intake and exhaust pipe 16. The engine is operated in the above described manner until the laminations 18 and 21 on the cap 115 piece 17 and the valve 20 respectively have been highly heated by the repeated explosions, that is, until said laminated portions are hot enough to ignite the explosive mixture formed by the relatively heavy oil in 120 the tank 91 and the air entering through the inlet pipe 30 and the intake and exhaust pipe 16. The laminations upon the valve 20 are especially effective because of the movements of the valve, for the reason that 125 these movements produce more or less surface friction with the combustible gases, and therefore more readily ignite the gases. When this condition exists the cams 84 and 88 are slid along shaft 80 to a position 130

where they will not engage with the rollers 83 and 89 respectively. The lever 100 is now operated to close the valve 95 and simultaneously open the valve 96, and the valve 5 112 is also closed, it being understood that the valve 66 has already been closed, as it will not be necessary to use the compressed air as a starting force except for the initial stroke of the piston, the heating operation 10 thereafter being effected by the explosive mixture formed by the volatile fuel. The engine will now operate with the heavy oil as a fuel and the repeated explosions will operate to maintain the laminated portions 15 17 and 21 heated to such a degree as will enable them to ignite the explosive mixture under compression. It may be noted that the piston only operates to compress the air within the explosive chamber and cylinder 20 which has been admitted through the intake and exhaust pipe 16 and that just before the end of the compression stroke of the piston the relatively heavy fuel is projected into the cylinder through the fitting 68. This 25 instantly mixes with the compressed air and forms the explosive mixture which is ignited by the heated laminated portions of the cap piece 17 and valve 20.

In Fig. 5 of the drawing I have shown 30 diagrammatically means whereby the valves controlling the intake and exhaust ports of two cylinders of a multi-cylinder engine may be controlled by a single crank upon the shaft 42. In this construction it will be 35 noted that the stem 35 extends through the partition 34 and is attached to a second valve member 114, which coöperates with an intake pipe 115 controlling the flow of air and the exhaust from a cylinder 116. In 40 this case, both the cylinders 116 and 3 utilize for exhaust purposes the common exhaust pipe 29.

It will accordingly be seen that I have 45 provided an engine of the type described which is exceedingly simple in construction and operation, the number of parts usually employed in engines of this character being greatly diminished. One advantage inherent in my construction resides in the fact 50 that I have provided a starting device which will operate with a minimum of consumption of compressed air. The ignition means, while exceedingly simple in construction, is nevertheless certain in operation, since the 55 parts being always maintained heated to a degree sufficient to ignite the explosive mixture, any chance of a cylinder missing fire is entirely eliminated.

It is especially pointed out that the use of 60 the opening 16 and the member 17 as a combined inlet and exhaust passage is especially desirable and effective for the reason that the ingoing air is heated to a high temperature from the walls of the opening, which 65 walls are maintained heated by the exhaust-

ing products of combustion. The air passes into the cylinder or combustion chamber in a heated condition and therefore readily mixes with the atomized fuel within the chamber. The same heated member which 70 heats this ingoing air is situated so as to stand in the path of the incoming fuel oil, and the heated condition of the member transforms the oil into a vapor within the chamber directly where the heated air enters, and these two fuel constituents readily combine to produce an efficient combustible mixture within the chamber.

Though I have shown and described the opening 16 to be adapted for the passage 80 of pure air, and the opening 67 to be adapted for the passage of a fuel oil for mixing with the air in the combustion chamber, it is apparent that the spirit of my invention includes the introduction through the openings 16 and 67 of relatively non-combustible fuel constituents, and that these two constituents are to be independently acted upon on entering the combustion chamber so as to adapt them for an immediate and intimate mixing whereby to form a relatively highly combustible mixture in the combustion chamber.

As many changes could be made in the above construction and many apparently 95 widely different embodiments of this invention could be made without departing from the scope thereof, it is intended that all matter contained in the above description or shown in the accompanying drawing shall 100 be interpreted as illustrative and not in a limiting sense. It is also to be understood that the language used in the following claims is intended to cover all of the generic and specific features of the invention herein 105 described and all statements of the scope of the invention, which as a matter of language, might be said to fall therebetween.

Having thus described my invention, what I claim as new and desire to secure by Letters Patent, is:

1. In apparatus of the class described, the combination with a cylinder, a piston and an explosion chamber, of a combined intake and exhaust pipe having a part projecting 115 into the explosion chamber, and ignition means carried by the part of said combined intake and exhaust pipe which projects into the explosion chamber adapted to be heated by the heat generated by the explosion with- 120 in the explosion chamber.

2. In apparatus of the class described, the combination with a cylinder, a piston, and an explosion chamber, of a combined intake and exhaust pipe leading into the explosion 125 chamber adapted to become heated by the exhausting products of combustion and thereby to heat the intake charge, and a laminated member adjacent said combined intake and exhaust pipe, the laminations of 130

which are adapted to become heated by the heat generated by the explosions within the explosion chamber whereby said laminations will operate as ignition means for the heated 5 intake charge.

3. In apparatus of the class described, the combination with a cylinder, a piston, and an explosion chamber, of a combined intake and exhaust pipe leading into the explosion 10 chamber, adapted to become heated by the exhausting products of combustion and thereby to heat the intake charge, a movable valve coöperating with said combined intake and exhaust pipe, and means carried 15 by said valve adapted, during the operation of the engine, to form ignition means for the heated intake charge.

4. In apparatus of the class described, the combination with a cylinder, provided with 20 a piston and an explosion chamber, a pipe leading into the explosive chamber adapted to conduct fuel oil thereinto, of a second pipe leading into the explosion chamber adapted to conduct air thereinto and through which 25 the products of combustion are discharged, whereby the second pipe is heated and adapted to heat the ingoing air, a valve co-operating to open and close said second pipe, and means carried by said second pipe and 30 by said valve adapted during the operation of the engine to constitute vaporizing means for the oil from the first mentioned pipe, and to constitute ignition means for the explosive mixture formed by the vaporizing 35 oil and the heated air.

5. In an internal combustion engine, the combination with a cylinder and a piston movable therein, of a combined inlet and exhaust opening into said cylinder, a valve 40 for controlling said opening and means adjacent said opening adapted to be heated by the hot gases passing through said opening

and to serve as an ignition means within said cylinder.

6. An internal combustion engine comprising a cylinder, a piston, an explosion chamber, a pipe leading into the explosive chamber adapted to conduct fuel oil thereinto, a second pipe leading into the explosion chamber adapted to conduct air there- 45 into and through which the products of combustion are discharged whereby the second pipe is heated and is adapted to heat the ingoing air, and means carried by said second pipe adapted during the operation 50 of the engine to constitute vaporizing means for the oil from the first mentioned pipe, and to constitute ignition means for the explosive mixture formed by the vaporized oil 55 and the heated air. 60

7. An internal combustion engine comprising, a cylinder, a piston, and an explosion chamber, said explosion chamber having two openings therein, one of said openings being adapted for the intake of one 65 fuel constituent, the other opening being adapted for the intake of another fuel constituent, and one of said openings being also adapted for the exhaust of the heated products of combustion, whereby the walls of 70 this opening become highly heated and serve to heat the fuel constituent entering therethrough, and the other opening being adapted to project its fuel constituent into contact with the heated walls of the first opening, 75 whereby to adapt its fuel constituent for better mixing with the heated fuel constituent from the first opening.

In testimony whereof I affix my signature in the presence of two witnesses.

MARIO CARBONE.

Witnesses:
